[57] ABSTRACT

In a cutter head for a dry shaver, a foil constituting an upper cutter is bent downwards at a margin to constitute an upper comb, a lower cutter and a lower comb constitute a unit which is reciprocated and urged upwards, but the lower comb is nevertheless a resilient part independent of the lower cutter.

CUTTER HEAD FOR DRY SHAVING APPARATUS

British patent specification No. 1,184,114 describes a cutter head for dry shaving apparatus, which includes an upper cutter and a lower cutter each formed of curved and yielding cutter foils. The curvature of the lower cutter foil is brought about by opposed forces, which are exerted on the foil by a tension member engaging opposed edge parts of the foil, and the entire lower cutter is pressed elastically against the upper cutter and is movable relatively to the latter in the cutting direction. According to the teaching of the above mentioned patent specification, the upper cutter foil is bent at its margins towards the concave side of its curvature, i.e., downwards, with the formation of edges, and the curved lower cutter foil in the immediate neighborhood of the bent edges of the upper cutter foil either terminates or is bent, while at least one bent edge of the upper cutter foil, and in the zone of the lower cutter foil which is adjacent to this bent edge, comb cutting parts are formed.

The present invention relates to a further development of this cutter head construction, which aims to ensure satisfactory cooperation of the upper cutter and lower cutter of the perforated cutting part on the one hand, and of both combs of each comb cutter part on the other hand, without the need for a specially high precision in the manufacture of the individual parts of the cutter head.

This is achieved according to the invention, in that the comb of the lower cutter unit, that cooperates with the comb on the upper foil, is not — as in the cutter construction described in the above mentioned patent specification — directly formed in a zone of the lower foil adjacent to a bent edge of the upper foil, but is formed on a resilient part independent of the lower foil for the perforated part.

Preferably the comb of the lower cutter unit is releasably mounted on a tension member for the lower foil.

When comb parts are formed on both sides of the perforated part, as is the case in a preferred constructional form of the invention, then the lower combs of the two comb parts are preferably formed on opposite marginal zones of a common metal foil; this metal foil may then be fastened to the tension member for the lower foil of the perforated part.

Further features of the invention appear from the following description of a constructional example, which is shown in the accompanying drawings. In these drawings:

FIG. 1 shows a cutter head schematically in cross section; and

FIG. 2 shows in perspective a portion of the marginal area of the cutter head, from which the cooperation of the three foils used in the cutter head can be seen.

A cutter head frame 1 is removably fixed to the upper part of the housing of the dry shaving apparatus. On the interior of the frame there are a plurality of inwardly directed noses 2, on which downwardly bent marginal strips 3d of a cutter foil forming the upper cutter of a perforated part are mounted by means of holes. In the curved upper part of the cutter foil 3 there are the usual sieve-like perforations 3a, whereas in the area of the two bent edges or bend lines 3c there are comb slots 3b.

In the interior of the cutter head frame 1 there is arranged a lower cutter unit, which, by means of known driving elements (not shown), is displaced in a reciprocatory motion in the direction perpendicular to the plane of the drawing, and by springs (not shown) is pressed resiliently into the concavity of the upper foil 3.

The lower cutter unit has a frame 4, which, on its upper side, carries engaging pins 4a for two parts of the unit. The lower cutter 5 of the perforated part is a curved metal foil, the side margins 5a of which are bent inwards and engaged on the pins 4a by means of holes. By this engagement of the side margins of the foil 5a, this foil is compelled into the desired curvature. The frame 4 thus acts as a tension member. The height of the curvature above a chord is advantageously at most equal to half the radius of curvature of the cutter foil at the apex of its curvature.

The lower combs 6a of two comb parts are each in the form of a row of slits on the bent side margins of a metal foil 6, which likewise engages on the pins 4a by means of holes.

It can be seen without more explanation, that in this construction the perforated or slit area of the lower foil 5, which cooperates with the perforated area 3a of the upper foil 3, and the two combs 6a, which cooperate with the combs 3b on the bent edges or bend lines 3c of the upper foil 3, are resilient independently of one another, and engage the upper foil 3 under this resilient action, so that for all parts of the cutter head a satisfactory cutting pressure is ensured.

Various modifications are possible within the scope of the invention. In particular it is possible to provide a comb part only on one side of the cutter head, while on the opposite side the corresponding part of the foil 6 is formed simply as a sliding guide.

I claim:

1. A cutter head for dry shaving apparatus comprising a perforated part including an upper cutter and a lower cutter, a comb part including an upper comb and a lower comb, said upper cutter comprising a yieldable foil which is completely curved convexly, said foil having marginal edges bent downwardly along a pair of spaced bend lines, said upper comb being formed along one of said bend lines, a head frame, said marginal edges being connected to said head frame beyond said upper comb, said lower cutter comprising a curved and yieldable foil having inwardly bent margins, a cutter frame, said inwardly bent margins being connected to said cutter frame, and said lower comb comprising a separate yieldable foil also connected to said cutter frame, so that said lower cutter and said lower comb constitute a unit which may be reciprocated relative to said upper cutter.

2. A cutter head as claimed in claim 1, including pins on said cutter frame extending between said lower cutter and said inwardly bent margins to fix thereby the curvature of said lower cutter, said lower comb being releasably mounted on said cutter frame by means of said pins.

3. A cutter head as claimed in claim 1, including another upper comb being formed along the other one of said bend lines, said upper cutter foil having cutting perforations therein located between said upper combs, said lower comb foil having opposing marginal zones, and said lower comb being defined by a row of slits located at said marginal zones.
